(57) **CLAIM**

We claim the ornamental design for a heart-sound and ECG sensor and adapter combination, as shown and described.

DESCRIPTION

FIG. 1 is a top perspective view of a heart-sound and ECG sensor and adapter combination showing our new design; FIG. 2 is an exploded perspective view thereof; FIG. 3 is a bottom plan view of the sensor portion thereof taken along the line 3-3 in FIG. 2; FIG. 4 is a top plan view of the adapter portion thereof taken along the line 4-4 in FIG. 2; FIG. 5 is a top plan view thereof; FIG. 6 is a side elevational view thereof, the opposite side view being a mirror image; FIG. 7 is a bottom plan view thereof; FIG. 8 is an end elevational view thereof; and, FIG. 9 is another end elevational view thereof. The dash-double-dot lines represent the environmental elements and form no part of the claimed design.
